HUGO SACK, OF DUSSELDORF, GERMANY; ADELHEID SACK ADMINISTRATRIX OF SAID
HUGO SACK, DECEASED.

UNIVERSAL ROLLS FOR ROLLING FLANGED BARS.

939,170.

Specification of Letters Patent.

Patented Nov. 2, 1909.

Application filed March 30, 1903. Serial No. 424,133.

To all whom it may concern:

Be it known that I, HUGO SACK, a citizen of the German Empire, residing at Dusseldorf, Rhenish Prussia, Germany, have invented certain new and useful Improvements in Universal Rolls for Rolling Flanged Bars, of which the following is a specification.

This invention relates to universal rolls for rolling flanged bars, being especially an improvement upon the universal rolls for rolling I-bars with flanges of uniform thickness throughout, of which flanges the narrow sides are square to the general direction of the flange but which have all edges rounded, such as are disclosed in my application, for United States Letters Patent, Serial No. 353,380, filed January 21, 1907. The distinguishing characteristic of such rolls is, that one of the vertical rolls is formed with annular working grooves each being in cross section rounded at the bottom, but with sides at right angles to each other, and, in like manner, the horizontal rolls are formed, on the side nearest the other one of the said vertical rolls, with similar annular grooves, rectangular in cross section but rounded at the corner. With this construction the result is obtained that, when the bar leaves the working stand to have its flanges straightened out in the straightening stand, said flanges are already rectangular, and of the required size, so that I-bars are obtained without any taper whatever. In such universal rolls, upon which the present invention is an improvement, the two annular surfaces of the said vertical roll which press against, and form, said narrow sides of the corresponding flanges, are extended outward almost in an uninterrupted surface, and the horizontal rolls are formed with undercut annular grooves, into which said extended portions enter, said extended portions of said surfaces of the vertical roll passing close to the surfaces of the horizontal rolls when they come to the plane of rolling. It has now been found that such rolls, when worn out after much use, could not be re-turned so as to have a proper configuration, because the change in the form of the rims or flanges of the vertical rolls due to the necessary re-turning could not be made to correspond with the change in the form of the grooves of the horizontal rolls, which grooves continually become

larger, as the result of continual re-turning. Consequently, fins are eventually formed on the girders.

The object of the present invention is to provide an improved form of these rolls by which this difficulty can be overcome.

In the accompanying drawing, Figure 1 is a view, partly in section, partly in broken front elevation, of a set of my improved universal roughing rolls for rolling I-bars, the 65 bearings being omitted from the drawing for simplicity of illustration; Fig. 2 is a similar view of a modification of the rolls; Figs. 3, 4, and 5 are diagrammatic views illustrating three consecutive passes through 70 the rolls.

Referring to the drawing, 1 indicates a pair of horizontal roughing rolls, substantially alike in form, and 2, 3, indicate a pair of vertical roughing rolls co-operating with 75 the rolls 1. At each side of the mill, the contour of the pressure surfaces of the vertical rolls is that of two straight lines 4 meeting at an angle. In like manner, the cross section, in the plane of rolling, of the 80 pressure surfaces of the two horizontal rolls includes two straight lines 5 which are respectively parallel to the above mentioned lines 4 of the contour of the pressure surfaces of the vertical roll. The result of this 85 construction is that, in the operation of rolling, the flanges of the bar are of uniform thickness throughout, this uniformity of thickness continuing from the first stage in the operation of rolling to the last, however 90 much the rolls may be caused to approach each other, so that, without at any time requiring any excessive rolling pressure, to cause any deformation in the shape of the flanges of the I-bar, but merely a general 95 elongation of said bar and a corresponding reduction in the thickness of the flanges, the I-bar is finally rolled out having flanges of uniform thickness throughout. The vertical roughing roll 2 is formed with horizontal 100 annular grooves 6, the cross-sectional form of such groove being a right-angled rounded corner, and each of the horizontal rolls is formed at the side of the mill next to the other vertical roll 3 with a similar vertical 105 annular groove 7. By reason of this construction it is possible to roll an I-bar, the flanges of which have narrow sides square to the general direction of the flange, and with corners rounded. After rolling the bar by 110.

means of the roughing rolls herein shown, the bar is finished in a set of finishing rolls, which merely straighten out the flanges. In the roughing rolls shown in my application 5 for patent above referred to, in the same way as the pressure surfaces 8 on the other side of the horizontal rolls, which press against and from, the narrow sides of one flange of the I-bar, are now still extended 10 outward in nearly the same general direction, as shown at 9, so also the pressure surfaces 10 of the vertical roll 2 which perform the function of pressing against, and forming, the narrow sides of the other flange of 15 the I-bar, were then extended outward very nearly in the same general direction as said pressure surfaces, and the horizontal rolls on the corresponding side were formed each with an undercut annular groove adapted 20 to receive said extensions, or flanges, of the vertical roll 2. With that construction, when the horizontal roll became unduly worn, a certain amount of the metal would be lacking, and a large recess would be 25 formed at the point where the extensions or edges of the flanges of the vertical roll should come into close proximity with the horizontal rolls. By my present construction I overcome this objection, by forming 30 the vertical roll 2 with surfaces 12 substantially parallel with the axis of the roll, and by also forming the horizontal rolls with surfaces 13, substantially at right angles to the axes of the latter rolls. On account of 35 this new form of the rolls, their life will be considerably lengthened, since no re-turning of the grooves of the horizontal rolls is now required, and the extension of the corresponding rims for the vertical rolls does not 40 tend to form any fins. This may be clearly seen from Figs. 3, 4, and 5, which show three consecutive passes through the rolls, the full lines indicating the outlines of the rolls, and therefore the cross section of the bar passing 45 between said rolls at that time, and the dotted lines *p* indicating the cross section of the bar produced by the preceding pass. It will be seen, from Fig. 3, for instance, that the sharp edge *e* of the bar made by the 50 preceding pass, is now rounded by the round corner 6 of the annular groove of the vertical roll, and a similar result is attained on the right hand side. Fins can never be formed at the open parts of the passes on 55 the left hand side, so that the grooves of the horizontal rolls, and the rims of the vertical roll projecting into said grooves, are no longer necessary.

In the modification shown in Fig. 2, instead of making the entire width of the surfaces 12 and 13 parallel with the axis of the vertical rolls, they are made so parallel only

for a part of their width; that is, the modification shown in Fig. 2 is intermediate in construction between the old form of the 65 rolls and the form shown in Fig. 1.

I claim:

1. A universal mill, consisting of a pair of horizontal rolls having working faces comprising an intermediate cylindrical surface and outwardly-extending frustoconical surfaces, and a pair of vertical rolls having convex faces opposed to said frustoconical surfaces, said rolls providing a pass comprising a web-portion and outwardly-diverging flange-portions, each horizontal roll having at one end a surface to shape the edge of a flange and at its other end a substantially vertical shoulder, and substantially cylindrical vertical-roll surfaces opposed to 80 said vertical, horizontal-roll shoulders.

2. A universal mill, consisting of a pair of identical asymmetrical horizontal rolls having working faces comprising an intermediate cylindrical surface and outwardly-extending frustoconical surfaces, and a pair of non-identical symmetrical vertical rolls having convex faces opposed to said frustoconical surfaces, said rolls providing a pass comprising a web-portion and outwardly-diverging flange-portions, said horizontal rolls having at one end surfaces to shape the edges of one set of flanges and at their other ends substantially vertical shoulders, and one vertical roll having surfaces to 95 shape the edges of the other set of flanges and substantially cylindrical surfaces opposed to said vertical horizontal-roll shoulders.

3. A universal mill, consisting of a pair 100 of horizontal rolls, and a pair of vertical rolls having duplicate convex working faces, said rolls providing a symmetrical pass consisting of a web-portion and outwardly-diverging flange-portions, the horizontal and 105 vertical rolls having adjacent surfaces arranged to press upon and form the faces of the flanges, and one vertical roll having annular surfaces arranged to press upon and form the edges of the flanges, said vertical 110 roll having surfaces 12 extending outward from said annular surfaces in a vertical plane, and the horizontal rolls having corresponding surfaces 13 which in the plane of rolling are substantially parallel with and 115 are adjacent to the surfaces 12, substantially as described.

In testimony whereof I have signed my name to this specification in the presence of two subscribing witnesses.

HUGO SACK.
